UNITED STATES PATENT OFFICE.

SIDNEY B. WHITESIDE, OF NEW YORK, N. Y.

ICE-CREAM-CAN TONGS.

Application filed August 31, 1926. Serial No. 132,735.

The present invention relates to a device for removing an interior container from an outer container, such, for instance, as the ice cream container from the container for the ice or freezing mixture, and for conveying said interior container by hand with ease and facility and without danger of soiling the material within the container in any way.

10 In the removal of an ice cream container from a freezer without the aid of an extracting means, it is necessary to grasp the top of the container and withdraw the same against the resistance created by the ice which is packed around the container and within the freezer. This oftentimes results in the accidental removal of the top from the container and the admixing of salt or ice from the freezing medium with the ice cream 20 with detrimental results. Moreover, in conveying the interior container filled with the ice cream, considerable difficulty is experienced because of the low temperature thereof which chills the person carrying said container when he employs only his arms to do so.

An object of the invention is to provide a device by means of which the inner container may be extracted with ease and without any possibility of the cover of the container becoming accidentally removed and by means of which the container may be carried around by hand conveniently and with facility.

35 With the above and other objects in view, the invention further resides in the details of construction more particularly pointed out in the following description of the accompanying drawings in which

40 Figure 1 is a view partly in section and partly in elevation, showing the application of my device to a container;

Figure 2 is a plan view of the device;

45 Figure 3 is a fragmentary sectional view on line 3-3 of Figure 1; and

Figure 4 is a fragmentary view of one of the engaging arms.

Turning now to the drawing, in which like reference numerals indicate like parts throughout the several views, the embodiment of the invention illustrated consists essentially of a pair of levers, 11 and 12, pivoted together at 13, as by means of a rivet. Lever 11 is provided with an intermediate portion 11^a in which the wide, flat side of the strip is in a substantially ver-

tical plane. The major upper portion of the lever 12 has its wide, flat side 12^a in a substantially vertical plane. These vertically extending flat portions give strength and 60 rigidity to the tongs, where most needed. This rivet is preferably provided with a reduced portion, 14, providing a shoulder against which the lever, 11, bears. By means of this construction, the rivet is rigidly associated with the lever, 11, but may rotate in the lever, 12, thus permitting the levers to be swung together or spread apart.

Each of the levers is provided with a claw portion, 15, which is bent in angular relation to the body portions of the levers and has a toe portion, 16, for the engagement of a flange, 11, extending around the periphery of the container, 18, and at the end thereof, said toe portions extending inwardly so that the ends thereof are adapted to engage beneath the flange, 17. In order to augment the efficiency of the engagement, the toe portions terminate in sharp edges, as best shown in Figure 4, which are slightly 80 curved so as to intimately embrace the exterior of the container and to effectively grip beneath the flange.

The lever, 11, is provided with an extending operating handle, 19, which in service 85 position is disposed above the lever, 12, as shown in Figure 1. This handle is preferably curved, as shown, to enable it to be grasped in the hand and to readily adapt it self to the same.

While the device may be made of any desirable rigid material, I prefer to make it of metal of strip form which may be bent into the desired shape to provide the claw portions, 15, and the handle, 19. The material, 95 steel, is found to possess particular utility in this connection, for with this material the toe portions, 16, may be tempered to give them great strength and durability and to enable them to successfully perform the task 100 for which they are designed.

In operation, the claws, 15, are separated by the pivotal movement of the levers, 11 and 12, to an extent sufficient to insure the passage of the toe portions over the flange of the container. The handle, 19, is then gripped by the user, whereupon any force applied to extract the container will force the claws so that the toe portions are urged into firm engagement with the container and beneath the flange thereof and any increase 110 in the extracting force will result in a like

increase in the gripping action of the claws. Thus, the container may be readily elevated by applying a lifting force to the handle, 19, and it may be carried about and transported by means of the device described with considerable ease and facility.

No one prior to myself has constructed an apparatus for the removal of an ice cream can from the container housing the same 10 which is both sanitary and easily operated. This has been due to the fact that the space between the can and container is very small, and it is extremely difficult to get a tool in the same. By means of the construction 15 above described, a tool which is both sanitary and easily operated is provided which may be slipped into the space between the can and the container and which is strong enough to lift the can out of the container 20 and to enable it to be carried around. The particular features of my device which render it successful in the use contemplated are that the thin widths of the levers occupy the spaces between the can and the container 25 and that the levers are jointed to provide regions of great strength and rigidity capable of withstanding the lifting force to which the tongs are subjected when the can is being withdrawn from the container.

It will be understood that the above description is to be construed merely as illustrative and that variations and alterations may be made in the specific structure disclosed without departing from the spirit of the invention or the scope thereof. 30

What I claim is:

Lifting tongs for ice cream cans, comprising two levers made of substantially flat and relatively wide strip material, an intermediate portion of one of the levers having its wide, flat side extending in a substantially vertical plane, the major upper portion of the other lever having its wide, flat side extending in a substantially vertical plane and being pivoted at its upper end to said 40 vertically disposed intermediate portion of the first lever, the upper portion of the first lever being extended to form a lifting handle, the lower, gripping ends of both levers being turned substantially ninety degrees and having their extreme ends formed into curved terminal toes for engaging under an abutment on the can to be lifted. 45

In testimony whereof, I have signed my name to this specification this 30th day of 50 August, 1926. 55

SIDNEY B. WHITESIDE.
